ABSTRACT OF THE DISCLOSURE

The invention provides a device for temporarily interrupting stitch formation in automatically controlled embroidery machines in which a rotating looper enters the thread loop formed by a needle fitted to the end of a reciprocating needle bar. The needle bar is rotatable through substantially a right angle in a dog imparting reciprocating motion to said needle bar which is slidable in an actuator ring for rotating said needle bar. This actuator ring is turnable by the plunger of a solenoid against the resistance of a spring which restores said actuator ring and said needle bar into their normal positions.

BACKGROUND OF THE INVENTION

The interruption of stitch formation in automatically controlled embroidery machines is desirable more particularly in multiple head machines when the frames are automatically moved from one part of the pattern to another, since this eliminates the undesirable creation of intermediate floating stitches underneath. These floating stitches must be pulled out by hand when the embroidery has been completed, work which takes some time to do.

Several methods have already been proposed for intermediately stopping the formation of stitches, for instance by preventing the descent of the needle bar and the needle from piercing the work. It has also been proposed to incorporate clutch means which retard the motion of the looper or to provide clutch means for rendering the needle bar inoperative altogether. In all these machines and mechanisms the arrangements are fairly complex and require considerable power for their operation. Furthermore, reactivation submits the parts to shock loads which cause premature wear.

SUMMARY OF THE INVENTION

It is the object of the present invention to overcome this drawback and to provide a device which is also capable of being subsequently fitted to an existing embroidery machine.

To attain this object the present invention provides a device for temporarily interrupting stitch formation in automatically controlled embroidery machines having a rotary looper which enters the thread loop formed by a needle fitted to the free end of a reciprocating needle bar, said device comprising a needle bar, a needle fitted to one end of said needle bar, a dog engaging said needle bar and imparting reciprocating motion thereto, an actuator ring for guiding said needle bar and rotating it about its axis through an angle of about 90°, a solenoid for rotating the actuator ring, and a tension spring for restoring said actuator ring and said needle bar into their normal positions.

Rotation of the needle bar carrying the needle prevents the looper from entering the thread loop and from forming a stitch.

Very little power is needed for thus turning the needle bar and the needle.

2

For returning the needle to its working position the actuator ring is connected to a torsion or tension spring. Substantially no wear is caused by the rotation of the needle through 90°.

Rotation can be imparted to the actuator ring by energizing the solenoids by means of the Jacquard card which controls the machine.

Thick gauge needles are formed with a transverse groove across the needle eye. The looper moves through this groove when it enters the thread loop. Rotation of such a needle would cause the needle to move into the range of the looper. This can be avoided by inserting the needle eccentrically into the needle bar in such a way that rotation of the needle bar will carry the needle out of range of the looper.

BRIEF DESCRIPTION OF THE DRAWING

An embodiment of the invention will now be described by way of example and with reference to the accompanying schematic drawing in which:

FIG. 1 is an elevational view of a needle bar;

FIG. 2 is a section taken on the line II—II of FIG. 1 but with the needle bar in raised position;

FIG. 3 is a top plan view of the needle bar;

FIG. 4 is a side view, of an enlarged scale, of a looper and a thicker needle formed with a transverse groove;

FIG. 5 shows the eccentric location of the needle in the needle bar in stitch forming position, and

FIG. 6 shows the eccentrically fitted needle in non-stitch-forming position.

DESCRIPTION OF THE PREFERRED EMBODIMENT

FIGS. 1 and 2 show a needle 1 and a looper 2 of an embroidery machine the movements of which are synchronized to enable the point 3 of the looper 2 to enter the loop of the upper thread formed by the needle 1. The looper 2 rotates in the arrowed direction 4. The needle 1 is attached to a needle bar 5 which reciprocates vertically, a movement which is imparted thereto by a dog 6 at the end of an arm 9 which derives reciprocatory motion in the direction of the double-headed arrow 10 from the main shaft of the embroidery machine.

For the purpose of stopping stitch formation the needle bar 5 and the needle 1 are rotatable about their axis through approximately a right angle. This rotation moves the thread loop of the needle 1 out of range of the looper 2 so that no stitch can be formed.

To achieve this end, the dog 6 is provided with a slot 11 engaged by a pin 12 fitted into the needle bar 5. The needle bar 5 can rotate in the dog 6 whilst continuing to be entrained thereby for up and down movement.

Moreover, an actuator ring 13 is loosely mounted on the needle bar 5. This actuator ring 13 contains a pin 15 engaging in a slot 14 in the needle bar 5. The actuator ring 13 is operable by the plunger of a solenoid 16 adapted to rotate the actuator ring 13 through an angle of about 90° by one or more interposed links 17. A tension spring 18 is adapted to turn back the actuator ring 13 into its normal position.

As will be understood from FIG. 3 a pin 19 connects the links 17 to the actuator ring 13 and is thus movable from position *a* into position *b*. The pin 15 engaging the slot 14 thus permits the needle bar 5 to be rotated and to be moved to and fro into practically any desired position. The solenoid 16 is preferably energized by pulses triggered by the Jacquard card controlling the embroidery machine.

Thicker needles 1a, particularly for edge embroidery, are formed with a transverse indentation 20 as shown in FIGS. 4, 5 and 6. If the needle bar 5 fitted with such a thicker needle 1a were turned through an angle of

roughly 90° the point 3 of the looper 2 which moves on the line 7 in FIGS. 5 and 6, would foul the solid part of the stem of the needle 1a. Consequently this needle 1a is eccentrically fitted to the needle bar 5. FIG. 5 shows the working position and FIG. 6 the nonstitch forming position after the needle bar 5 has been turned through roughly a right angle in the direction of arrow 8.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description.

What is claimed is:

1. A device for temporarily interrupting stitch formation in automatically controlled embroidering machines having a rotary looper which enters the thread loop formed by a needle fitted to the free end of a reciprocating needle bar, said device comprising:
  - (a) a needle bar;
  - (b) a needle fitted to one end of said needle bar;
  - (c) a driven dog engaging said needle bar and imparting reciprocating motion thereto;
  - (d) an actuator ring, means guiding said needle bar for axial movement in said actuator ring, connecting means between said actuator ring and said needle bar for preventing relative rotary movement;
  - (e) a solenoid, means mechanically connecting said solenoid to said actuator ring for rotating said actuator ring and said needle bar through an angle of about 90 degrees from their normal positions; and

(f) a tension spring connected to said actuator ring and biasing said actuator ring and said needle bar into their normal positions.

5 2. A device according to claim 1, wherein Jacquard card means control the operation of said machine and means connecting said solenoid to said Jacquard card means whereby said solenoid is energized by pulses triggered by said Jacquard card means.

10 3. A device according to claim 1, wherein means mount said needle in the lower end of said needle bar in an eccentric position to the axis of said needle bar, a transverse indentation across the shank of said needle whereby the looper will clear the needle shank when said needle bar and needle are rotated from their normal positions.
